(57) **CLAIM**

The ornamental design for a sub-frame rear triangle as shown and described.

DESCRIPTION

FIG. 1 is a bottom, front and left perspective view of a sub-frame rear triangle showing my new design;

FIG. 2 is a top, rear and right perspective view;

FIG. 3 is a front elevational view thereof;

FIG. 4 is a rear elevational view thereof;

FIG. 5 is a bottom plan view thereof;

FIG. 6 is a top plan view thereof;

FIG. 7 is a left view thereof; and,

FIG. 8 is a right view thereof.

The evenly broken lines illustrate portions of the sub-frame rear triangle that form no part of the claimed design.
